REVERSIBLE CHAIR

Ira Rakatansky, Providence, R. I.

Application July 2, 1949, Serial No. 102,898

7 Claims. (Cl. 155—183)

1

This invention relates to improvements in the construction of an article of furniture and more particularly to an improved chair construction.

One of the primary objects of the present invention is to provide a chair which will serve the dual function of a straight back dining chair in one position and a reclining or lounge chair in another position.

Another object of this invention is to provide a chair of such construction that the various component parts may be packed in a compact knockdown form for shipment and still be easily assembled without resorting to expensive tools nor extensive mechanical experience.

Another object of this invention, in one embodiment, is to cut all the wooden parts from one sheet of plywood, thereby reducing waste material in the chair's manufacture.

Still another object of the invention is to provide a chair construction which will be light in weight, sturdy and durable in construction, artistic and attractive in appearance and be particularly comfortable to the human form.

Other objects of this invention will be pointed out in part and become apparent in part in the following specification and claims.

In a city apartment or other abode cramped for space, the present invention solves the utility problem by providing multiple functioning furniture in a single construction. Lawn furniture is similarly serviced thereby saving the cost of a second chair. Convenience by having two different light weight chairs handy is another feature of this novel chair.

In the preferred embodiment of the present invention the chair comprises four units. Two side pieces or frames, two arm rests which serve as base pieces in inverted position, two back plates plus supports and a seat. These pieces may be modified to change the artistic appearance of the chair but the objects of utility will remain as the invention.

Like reference numerals refer to like parts. In the accompanying drawings:

Figure 1 is a perspective view showing the chair in lounge or reclining position.

Figure 2 is a perspective view showing the chair in dining or straight back position.

Figure 3 is a side elevational view of the chair as viewed from the far side of the Figure 1 position.

Figure 4 is a side elevational view of the chair as viewed from the far side of the Figure 2 position.

Figure 5 is a plan view of all the wooden parts when cut from one sheet of plywood.

Figure 6 is a front elevational view showing a comparison of the sitting heights of the chair in the two serviceable positions.

Figure 7 is a plan view showing a comparison of the widths of the chair in the two serviceable positions.

Part of the novelty in this invention resides in the frame of the chair which when viewed in Figure 1 comprises a seat supporting frame portion 10 having an upright leg 11 and downward leg 12 forming an integral part thereof. The shape approximates the letter Z.

The rear corresponding frame member comprises a seat supporting frame portion 13 having upright leg 14 and downward leg 15. These frame members are held in spaced relation by means of cross arms 16 and 17 which are secured to upright legs 11 and 14 with screws 18, 19, 20 and 21.

Another set of cross arms 22 and 23 hold downward legs 12 and 15 in spaced relation. Screws 24, 25, 26 and 27 secure these parts together.

A back rest 28 is secured to cross arms 16 and 17 by means of screws 30, 31, 32 and 33. Another back rest 34 is secured to cross arms 22 and 23 by means of screws 35, 36, 37 and 38.

The seat of this novel chair as shown in the preferred embodiment of the invention consists of a series of slats 40 held in spaced relation by filler pieces 41 on the front edge, Figure 1, and by filler pieces 42 on the rear edge. A piece of drill rod 43 passes through slats 40, filler pieces 41 and is secured to leg 12 with nut 44 and to leg 15 with nut 45.

A similar piece of drill rod 46 passes through slats 40, filler pieces 42 and is secured to leg 11 with nut 47 and to leg 14 with nut 48.

As shown in Figure 2, slats 40 and filler pieces 41 and 42 may be held together and to frame seats 10 and 13 by means of glue or other adhesive. It is also contemplated to provide a solid seat made of wood, metal or plastic or a cushioned seat in place of the slat seat as illustrated. The same fastening means may be employed.

Referring to Figure 1, two members having the general shape of the letter Z are provided. As viewed in Figure 1, the body portion of the Z on the near side is indicated by the reference character 50. The upper portion or leg 51 is shaped into an arm rest. The lower portion or leg 52 is preferably given a straight form. Leg 51 is secured to upright 11 by means of screw 53. Leg 52 is secured to downward leg 12 by means of screw 54.

Still referring to Figure 1, the body portion of the Z on the far side is indicated by reference

character 55. The upper portion or leg 56 shaped into an arm rest is secured to upright 14 with screw 57. Lower portion or straight leg 58 is secured to downward leg 15 with screw 59.

These Z members are shown as comprising a square tube made of aluminum. They could be made of many other shapes in cross section and be made of many types of material, yet encompass the spirit of this invention which is to provide a chair having two different sitting positions.

The Z form of the chair frame in combination with the manner of securing the Z-shaped aluminum legs to said frame allows a comfortable spring motion to be imparted to the sitter in the chair.

Referring to Figure 5, it will be seen that the various parts may be cut from one piece of board or plywood or sheet of metal, 60.

Comparing Figure 1 with Figure 2 and Figure 3 with Figure 4, it will be seen that resting arms in Figures 1 and 3 are the base supports in Figures 2 and 4. The chair is turned upright down. Referring to Figure 6, it will be noted that dimension A when the chair is used in upright, straight back position, is greater than dimension B and back plate 34 dimension J is smaller than back plate 28 dimension K.

Similarly, it will be observed in Figure 7 that width C of the chair is less than width D when the chair is used in upright or straight back position. The rear portion of the chair E remains constant. Dimension F is less than dimension G and height H is greater than height I. This latter condition is due to the angle of inclination of seat dimension G created by the difference in the shape of legs 56 and 58 of the Z member.

The different dimensions provide comfort for the person sitting in the desired position. The chair is narrow when sitting upright and wide when reclining.

What I claim is:

1. A reversible chair comprising two side members, each provided with a seat supporting frame portion and an upward and downward leg portion, a seat member secured to said seat supporting frame portions, cross arms secured between said upward and downward leg portions, back pieces secured to said cross arms and two Z-shaped members secured to an upright and downward leg portion of each of said side members, respectively.

2. A reversible chair comprising two side members, each provided with a seat supporting frame portion and an upward and downward leg portion of each of said side members, a seat member secured to said seat supporting frame portions, cross arms secured between said upward and downward leg portions of each of said side members, back rests secured to said cross arms and two Z-shaped members secured to an upward leg portion at one end and to one of said cross arms on the opposite end.

3. A reversible chair comprising sides having a seat supporting frame and substantially oppositely disposed legs, slats running parallel to said seat supporting frame and separated by filler pieces, a pair of backs secured to said legs and

projecting above and below said seat supporting frame and a pair of Z-shaped members having oppositely disposed arm pieces secured to said oppositely disposed legs.

5. A reversible chair comprising a seat supporting frame, a seat fastened to the seat supporting frame, upper and lower legs secured to the sides of the seat supporting frame with the outer ends of the upper legs projecting above and the outer end of the lower legs projecting below the seat supporting frame, backs secured to the legs above and below the seat supporting frame and Z-shaped members secured at one end to the body portion of the legs above the seat supporting frame and to the edges of the legs below the seat supporting frame.

6. A reversible chair comprising a seat supporting frame, upper and lower legs secured to sides of the seat supporting frame with the outer ends of the legs projecting above and below the seat supporting frame, cross arms secured to the legs above and below the seat supporting frame, back rests secured to said cross arms, a seat comprising a series of slats and filler pieces, a rod connecting the upper legs of the seat supporting frame and one end of slats and filler pieces, another rod connecting the lower legs of the seat supporting frame and opposite ends of the slats and filler pieces and Z-shaped members secured at one end to the body portion of the one set of legs and to the ends of the other set of legs.

7. In a reversible chair the combination of cross arms, a pair of Z-shaped frame members connected to said cross arms, backs secured to said cross arms, a series of slats forming a seat secured to the middle member of the Z and another set of substantially Z-shaped members secured to said cross arm members.

8. In a reversible chair the combination of cross arms, a pair of approximately Z-shaped frame members connected to said cross arms, backs secured to said cross arms, a seat secured to the middle portions of said Z-shaped members and another set of substantially Z-shaped members secured to said cross arm members.

IRA RAKATANSKY.
